PRESSURE OPERATED VALVE FOR IRRIGATION SPRINKLERS

Charles J. Flynn, Glendora, Calif., assignor to Rain Bird
Sprinkler Mfg. Corp., Glendora, Calif.

Filed Oct. 7, 1974, Ser. No. 512,696

Term of patent 14 years

Int. Cl. D23—01

U.S. Cl. D23—19

Fig. 1

Fig. 2

Fig. 3

Fig. 4

FIG. 1 is a perspective view of a pressure operated valve for irrigation sprinklers embodying my new design;
FIG. 2 is a side elevational view thereof;
FIG. 3 is a top plan view thereof; and
FIG. 4 is a bottom plan view thereof.

I claim:

The ornamental design for a pressure operated valve for irrigation sprinklers, substantially as shown.
